UNITED STATES PATENT OFFICE.

HARRY D. LATHROP, OF CHICAGO, ILLINOIS.

CAN-WASHING MACHINE.

1,378,245.

Specification of Letters Patent. Patented May 17, 1921.

Application filed August 25, 1919. Serial No. 319,801.

To all whom it may concern:

Be it known that I, HARRY D. LATHROP, a citizen of the United States, and a resident of the city of Chicago, county of Cook, and 5 State of Illinois, have invented certain new and useful Improvements in Can-Washing Machines, of which the following is a specification.

My invention relates to improvements in 10 can washing machines, and more particularly to the discharge mechanism thereof, the object of the invention being to provide means for lessening the noise and shock commonly present in such machines.

15 Other objects will appear hereinafter.

The invention will be best understood by reference to the accompanying drawings forming a part of this specification, and in which,

20 Figure 1 is a longitudinal section taken through the discharge end of a well-known form of can washing machine, equipped with means embodying my invention.

Fig. 2 is an end view thereof.

25 The approved form of construction, as illustrated in the drawings, comprises a depending gravity-held swinging stop 3, mounted to swing freely on a transverse shaft 4 of the can washing machine and set in the path of the tops of cans 5 being discharged therefrom. In the normal operation of the machine, the cans are placed in the reversing saddle 6 by which they are automatically reversed or upended and discharged from the machine, sliding down the discharge chute or platform 7. The stop plate 3 is set in the path of the cans as they thus move from the saddle 6, so that the top edges of the cans come in contact with said 30 stop during their discharge movements.

40 The stop 3 thus yieldingly resists the discharge and reversing movement sufficiently to lessen the noise and shocks incident thereto, but yields sufficiently to permit the ready 45 passage of the cans in discharging. By this

arrangement the noise and shocks commonly present in such machines are materially lessened without impairing the efficiency thereof.

While I have illustrated and described the 50 preferred form of construction for carrying my invention into effect, this is capable of variation and modification without departing from the spirit of the invention. I, therefore, do not wish to be limited to the 55 precise details of the construction set forth, but desire to avail myself of such variations and modifications as come within the scope of the appended claims.

Having described my invention, what I 60 claim as new and desire to secure by Letters Patent, is:—

1. The combination with the can discharging mechanism of a can washing machine, of a stop set in the path of a can 65 being discharged, said stop being arranged to yield and be forced from said path by the can itself, substantially as described.

2. The combination with the can discharging mechanism of a can washing machine, of a gravity-held depending swinging stop, set in the path of a can being discharged therefrom, substantially as described.

3. The combination with the can reversing and discharging mechanism of a can washing machine, of a gravity-held depending swinging stop, adapted to contact with the tops of cans being reversed and discharged therefrom, to yieldingly resist the 80 movement of said cans, substantially as described.

In testimony whereof I have signed my name to this specification in the presence of two subscribing witnesses.

HARRY D. LATHROP.
